UNITED STATES PATENT OFFICE.

JAY B. CARROLL, OF SANBORN, IOWA.

ANGLE-COCK.

1,128,846.

Specification of Letters Patent. Patented Feb. 16, 1915.

Application filed April 20, 1914. Serial No. 833,177.

To all whom it may concern:

Be it known that I, JAY B. CARROLL, a citizen of the United States, residing at Sanborn, in the county of O'Brien, State of Iowa, have invented certain new and useful Improvements in Angle-Cocks; and I do hereby declare the following to be a full, clear, and exact description of the invention, such as will enable others skilled in the art to which it appertains to make and use the same.

This invention relates to angle cocks, particularly adapted for use on train pipes of automatic air-brake systems.

An object of the invention resides in the provision of an angle cock in which the operating handle is securely locked in either its open or closed position, the valve in said cock being so constructed and arranged therein, as to be automatically loosened from its seat when the handle is moved to an unlocked position, and thus may be readily turned to open or cut off communication between the train pipe and the coupling.

A further object of the invention is to provide an angle cock having a relief port adapted to communicate with the air-hose, when the valve is in its cut-off position, for the purpose of reducing the air therein to atmospheric pressure, so that when uncoupling, the customary breaking, tearing, or stretching of the hose is entirely obviated.

With the above and other objects of similar nature in view, the invention consists in the construction, combination, and arrangement of parts set forth in and falling within the scope of the appended claim.

In the drawings: Figure 1 is a side elevation of an angle cock constructed in accordance with the invention, Fig. 2 is a top plan view thereof, Fig. 3 is a sectional view on the line 3—3 of Fig. 2, with the valve in its open position, Fig. 4 is a similar view with the handle in its unlocked position, and the valve raised from its seat preparatory to cutting off the cock, Fig. 5 is a similar view with the valve in its cut-off position, and Fig. 6 is a section on the line 6—6 of Fig. 5.

Referring now to the drawing, the numeral 10 designates the casting of the cock, having a threaded passage 11 which communicates with the train line, and a threaded passage 12 communicating with the flexible hose that is coupled together between the cars, and being further provided with

an opening 13, threaded to receive a cap nut 14.

The casting 10 is also formed with a tapered bore 15, in which a tapered bushing 16 is permanently seated, said bushing having 60 openings 17 and 18 which communicate respectively with the passages 11 and 12 of the casting. The bushing 16 is also provided with an opening 19, which communicates with the relief port 20 formed in the 65 lower end of the tapered bore 13. Fitted in the bushing 16 is a tapered valve 21, said valve being formed with a transverse passage 22 adapted to be brought into communication with the passages 11 and 12 in the 70 angle cock to supply the train line with air. Formed in the valve 21, is a longitudinal groove or channel 23 which, when the valve is closed, establishes communication between the passage 12 and the relief port 20 75 to permit the air in the hose to escape to the atmosphere and thus facilitate the coupling being broken, without the usual stretching or tearing of the hose. Formed integral with the valve 21 and projecting 80 through the opening 24 in the cap nut 14, is a stem 25, the upper end of which is squared and terminally provided with a short notch 26 and a long notch 27, the former indicating the side of the valve in 85 which the groove or channel 23 is formed, and the latter indicating the direction of the air passage through the valve. It is thus apparent that, when coupling or uncoupling cars, say in the dark, the position 90 of the passage 22 and the channel 23 may be quickly determined by passing the finger over the notches 26 and 27, thereby enabling the operator to move the valve in the proper direction to effect the desired result.

For the purpose of operating the valve there is provided a handle 28, having a slotted opening 29 adapted to receive the squared end of the stem 25, the pin 30 in the stem 25 serving to prevent accidental 100 displacement of the handle and being also adapted to coact therewith to loosen the valve 21 from its seat. The handle 28 is provided on the end adjacent the stem 25, with a downward projection or fulcrum 31 105 adapted to engage the upper face of the cap nut 14 for the purpose to be presently explained. Also formed on the handle 28 is a locking finger 32 which, when the valve is turned, engages in one of the notches 33 110

in the casting 10 to retain said valve in either its open or closed position. Seated within the recess 34 formed in the under face of the cap nut 14, and encircling the stem 25, is a helical spring 35 said spring being compressed between the nut and the tapered valve 21 and normally tending to seat said valve tightly within the tapered bushing 16.

10 In operation, to open or close the valve, the handle 28 is rocked upwardly to disengage the finger 32 from one of the notches 33 in the casting 10, the downward projection 31 bearing against the upper face of the cap nut 14 to form a fulcrum for the handle, and that part of the handle adjacent the stem 25 engaging the pin 30 therein. The handle 28 is now employed as a lever to loosen the valve 21 from its seat, continued

15 upward movement thereof on the fulcrum 31 raising said valve in the bushing 16 and against the tension of the spring 35, to permit of the valve being readily turned to the desired position.

20 25 It will be noted that when the operator is at the air hose end 12 of the angle cock 10 and facing the angle cock, the long notch 27 is always in the same direction as the handle 28, and the notch 26 is at the left

20 30 of the handle. Thus when operating the lever is always pushed to the right one-fourth of a turn in order to shut off the valve and is lengthwise with angle cock 10 when valve is opened to connect air passage with train

35 pipe and air hose. It will further be noted

in Fig. 5 of the drawing, that the channel 23 is formed in the face of the valve 21 and centrally of the passage 22, thus when the angle cock is closed, communication between the passages 11 and 12 is completely shut off 40 prior to the establishment of communication between the passage 12 and the relief port 20, and the consequent reduction of pressure in the hose effected.

From the foregoing it will be observed 45 that there is provided an improved angle cock of simple and novel construction, and one that is fully capable of performing its various functions in a wholly efficient manner.

50

What is claimed is:

An angle cock comprising a casing having a bore, a valve seated in the bore and having oscillatory and reciprocatory movement therein, a lever connected with the valve for 55 oscillating and reciprocating same, a projection on said lever at one side of the valve in position to fulcrum on the casing, a locking member on the lever at the other side of said valve, a coöperating locking member 60 carried by the casing, and means for holding the valve yieldably with the locking member engaged.

In testimony whereof, I affix my signature, in the presence of two witnesses.

JAY B. CARROLL.
